(57) **CLAIM**

The ornamental design for a silverware drawer organizer as shown and described.

DESCRIPTION

FIG. 1 is a top perspective view of a silverware drawer organizer showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a top perspective view of the silverware drawer organizer in an expanded state of use; and,

FIG. 9 is an enlarged view of portion marked as 9 in FIG. 8.

Broken lines in the drawings depict portions of the silverware drawer organizer that form no part of the claimed design.

1 Claim, 9 Drawing Sheets
